COMBINATION OIL AND GAS BURNER

Smith E. Henson, Joplin, Mo.

Application February 17, 1939, Serial No. 256,990

3 Claims. (Cl. 158—11)

This invention relates to combination oil and gas burners, and has for one of its objects the production of a simple and efficient burner formed with passages each of which is constructed intermediate its length to provide an air intake at one end and an outlet at its other end, the said passages extending transversely of the burner and arranged throughout the length thereof, and which is also constructed in a manner to facilitate combustion and to produce a maximum of B. t. u.'s or heat units per foot of gas consumed.

A further object of this invention is the production of a simple and efficient burner constructed of metal, refractory material or other similar material in a manner to efficiently support the ignition plate which may be formed of carbofrax or refractory material, and hold the same rigid at all times.

Other objects and advantages of the present invention will appear throughout the following specification and claims.

In the drawing:

Figure 1 is a perspective view of the burner, a certain portion thereof being shown in section;

Figure 2 is an irregular vertical sectional view taken through one of the air passages of the burner;

Figure 3 is a sectional perspective view of a part of the burner;

Figure 4 is a horizontal sectional view taken on line 4—4 of Figure 2;

Figure 5 is an enlarged sectional view taken on line 5—5 of Figure 2.

By referring to the drawing, it will be seen that 10 designates the body or hull of the burner which is preferably formed of metal, refractory material or the like, and is adapted to support the ignition plate 11 preferably formed of carbofrax or other suitable refractory material.

The body or hull 10 preferably comprises an elongated box-like structure or rectangular casing having upper and lower parallel flanges 12 and 13 projecting from the casing. The ignition plate 11 is fitted between these flanges 12 and is firmly held in engagement with the body or hull 10 by means of the headed lugs 14. These headed lugs

14 are formed integral with the body or hull 10 and carry enlarged heads 15 around which the ignition plate of refractory material and the like is molded, thereby providing a unitary structure for the body 10 and ignition plate 11. Any number of these lugs 14 may be located throughout the length of the burner to firmly hold the ignition plate in engagement with the body.

The body 10 of the burner is provided with a central partition 16 for separating the body or hull 10 into a bottom liquid fuel compartment or reservoir 17, and a top gas compartment or reservoir 18. The casing or hull 10 and the ignition plate 11 are provided with diamond-shaped passages 19 which extend transversely of the burner, the passages contracting toward the adjoining faces 20 of the body or hull 10 and ignition plate 11, as shown in Figure 2. Preferably the corners 10 of these passages 19 are rounded so as to eliminate sharp or abrupt turns and thereby reduce noise. By considering Figure 2 it will be seen that the passage 19 illustrated therein tapers toward its center or the junction faces 20, as 18 above stated, and flares outwardly toward the inlet and outlet ends of the passage 19. The body or hull 10 of the burner is provided with a gas entrance port 21 communicating with the gas compartment or reservoir 18 and a liquid fuel entrance port 22 communicating with the liquid fuel compartment or reservoir 17. These ports 21 and 22 are suitably threaded for the purpose of receiving the supply pipes 23 and 24 respectively, as indicated in dotted lines in Figure 2.

Suitable orifices 25 are formed or drilled in the side walls of the diamond-shaped air passages 19 and are preferably formed in the left-hand walls thereof, as shown in Figure 1. An integral deflector lip 26 is carried by the walls of the air passages adjacent each orifice and in a position to overhang the same, as shown in the drawing, and are inclined inwardly so as to direct the oil vapor and gas in the direction of the ignition plate 11. In other words, these lips or jigs 26 are 30 inclined at a proper angle to cause either the natural gas or the vapor from the liquid fuel to be properly directed against the carbofrax ignition plate 11.

From the drawing, it will be noted that there 40 has been produced a burner which may be economically constructed and which may be operated at a minimum cost, and it should be further understood that there has been produced a burner which will operate efficiently on a gas pressure 45 of approximately one ounce or more and which will not require a motor or other power to vaporize the gas or liquid fuel.

When the burner is in operation, the ignition plate 11 vaporizes the oil or liquid fuel into a gas, 50 which fuel is delivered direct from the fuel chamber 17 through the orifices 25 leading from this chamber, the fuel passing into the diamond-shaped air passages 19, the air entering the outer ends of the passages 19 and passing through and 55

being discharged through the inner ends of the passages on the side of the burner adjacent the ignition plate 11. The heat of the ignition plate causes the natural gas to expand before it is delivered to the orifices 25 of the burner, thereby creating a pressure within the hull 10 of the burner and converting a low pressure gas into a high pressure gas. This converted high pressure gas is then delivered directly through the orifices 10 25 out into the air passages 19 in the direction of the ignition plate 11 where the gas is burned before the gas has time to contract, in this way obtaining maximum B. t. u.'s in proportion to the gas consumed.

15 As shown in the drawing the burner is provided with the central partition 16 running longitudinally through the hull or body 10 from end to end and centrally thereof, in this way providing the lower oil or liquid fuel reservoir 17 and the upper 20 gas reservoir 18. Because of this structure it is practical to use the burner to burn either of the fuels separately, or both fuels simultaneously. In other words, one-half of the burner running lengthwise carries the liquid fuel and the other 25 half carries the natural gas.

The heat from the ignition plate 11 heats the liquid fuel to convert the liquid fuel into a vapor which is then delivered directly through the orifices 25 into the mixing chambers or air passages 19. The vapor is delivered through the orifices 30 25 into the diamond-shaped air passages formed in the hull of the burner and the natural gas or vapor from the liquid fuel is directed against the carbofrax ignition plate 11 through the medium 35 of the lips 26 keeping the ignition plate at a desired temperature at all times. The lugs 14 will firmly hold the ignition plate in engagement with the hull 10 and in a rigid position.

As shown and previously described, the air 40 passages 19 which are preferably diamond-shaped extend through the hull and are surrounded by walls 27 and these walls 27 in conjunction with the spaced outer wall of the hull 10 will provide a circulating compartment or passage through 45 which the fuel may freely circulate and communicate with the respective ports 21 and 22 whereby the fuel may be replenished to the reservoirs 17 and 18. The passages 19 are used as mixing chambers and the throat of each air passage 19 by being restricted at the junction of the hull with the ignition plate at the face indicated by the numeral 20 and which is located approximately at the center of each diamond-shaped air passage causes the air entering the 50 passage to be delivered to the throat of the burner from its entrance end at a high rate of speed and the restriction of this passage 19 centrally will reduce the speed of the air to a very low velocity causing the heat from the fuel to remain 55 in the firebox or furnace much longer than would be possible if the air rushed through at a high rate of speed. It will be noted that the carbofrax ignition plate 11 is of suitable thickness and projects over the inner face of the hull of the burner 60 in a manner to properly protect the same from the heat from the furnace. It is preferable to

provide oval-shaped corners at the junction of the walls of the air passages 19 and to round the outside edges thereof to eliminate the passage of air over sharp corners thereby producing a burner which is practically noiseless.

The Venturi shaped passage takes the air from the outside at a high velocity, and when it passes through the throat of the burner, which is shown at 20, it causes the air and gas to pass that point at a low speed, which is delivered direct through 10 the flaring portion of the passage in the carbofrax face. The larger end of the flaring portion of the passage is at the outside of the carbofrax ignition plate which is inside the firebox or boiler. This causes the air and gas to pass through the 15 firebox at a very slow speed.

Having described the invention, what is claimed is:

1. A burner of the class described comprising a hollow body having a liquid fuel reservoir and a gas fuel reservoir, the body having a plurality of transversely extending air passages extending from the outer face to the inner face thereof, an ignition plate fixed against the inner face of the body and having passages communicating with and providing continuations of the air passages in the body, said body having orifices formed in the walls of the air passages for delivering fuel from the respective reservoirs into the air passages, and integral lips extending from the walls of the air passages at an incline toward said ignition plate and extending across said orifices in spaced relation thereto for directing the fuel toward the ignition plate.

2. A burner of the class described comprising a hollow body having a liquid fuel reservoir and a gas fuel reservoir, the body having a transversely extending air passage extending from the outer face to the inner face thereof, an ignition plate fixed against the inner face of the body and having a passage registering with and providing a continuation of the air passage in the body, the companion passages in the body and in the ignition plate being constricted toward their junction to provide a restricted throat, and said body having orifices formed in the walls of the passage formed therethrough for delivering fuel from the respective reservoirs into the said air passage.

3. A burner of the class described comprising a hollow body having a liquid fuel reservoir and a gas fuel reservoir, the body having a plurality of transversely extending air passages extending from the outer face to the inner face thereof, an ignition plate fixed against the inner face of the body and having passages communicating with and providing continuations of the air passages in the body, upper and lower flanges carried by the body and overlying the upper and lower faces of the ignition plate, headed lugs carried by the body and embedded in the ignition plate for holding the ignition plate rigidly against the body, and said body having orifices formed in the walls of the air passages for delivering fuel from the respective reservoirs into the air passages.

SMITH E. HENSON.
